UNITED STATES PATENT OFFICE.

JOSEPH S. OECHSLE, OF PHILADELPHIA, PENNSYLVANIA, ASSIGNOR TO METALWELD SERVICE CORPORATION, OF PHILADELPHIA, PENNSYLVANIA, A CORPORATION OF PENNSYLVANIA.

MARINE UNIT.

Application filed August 7, 1924. Serial No. 730,789.

To all whom it may concern:

Be it known that I, JOSEPH S. OECHSLE, a citizen of the United States, residing at Philadelphia, in the county of Philadelphia and State of Pennsylvania, have invented certain new and useful Improvements in Marine Units, of which the following is a specification.

This invention relates to marine propulsion and more particularly to power units adapted for installation in light draft vessels, and craft for use in shallow waters, the primary object being to provide a self-contained, one-man controlled, motive organization of dependable character and increased efficiency as compared with prevailing units of analogous type.

Another object of this invention is to utilize a standard type of tractor engine devoid of its wheels and axles as a marine engine.

Other objects associated with this invention are the provision of a marine unit of the foregoing type with a novel semi-automatic control mechanism; to improve the engine cooling system; to provide a rigid and stable base for said unit whereby vibration is to all practical intent eliminated; and to furnish a marine unit adapted to operate other utilities concurrently with, or independently of, propulsion.

Accordingly my present invention consists of the improvements hereinafter described whereby the above specified objects and results are attained; said improvements comprising certain structural features as well as the organization and combination of parts which are fully set forth hereinafter, and more particularly defined by the subjoined claims.

In the further disclosure of this invention reference will be had to the accompanying sheets of drawings illustrative of an actual embodiment thereof, and in which like or corresponding parts are designated by the same reference numerals throughout all the views.

Figure 1—is a perspective elevation of my novel marine unit as viewed from the rear.

Figure 2—is a perspective side view thereof.

Figure 3—is an elevation of the unit as viewed from the opposite side of the preceding figure.

Figure 4—is a detail front end elevation of the engine and associated circulating pump.

Figure 5—is a face view of a circulating connection hereinafter more particularly referred to.

Figure 6—is an edge view of the same.

Figure 7—is a detail side view of a box-bearing later on fully explained.

Figure 8—is a view at right angles to the preceding figure with a gland member removed to better illustrate certain otherwise hidden parts.

Figure 9—is a detail plan view of the circulating pump base support.

Figure 10—is an elevation of the same.

Figure 11—is a detail view of a coupling gland.

Figure 12—is a view at right angles thereto; and

Figure 13—is a detail view of a cam lever hereinafter fully explained.

Referring more in detail to the drawings and especially to Figures 1 to 3, a conventional type of tractor engine—for example a Fordson—is comprehensively designated by the numeral 13, and it will be noted that said engine is supported on a basal framework 14 of standard, longitudinally disposed, sections 15 with integrally lock-welded transverse sections 16 of like cross section. This basal framework 14 may be bolted or otherwise mounted on the deck of a light draft vessel by means of lag screws—not shown—with a minimum expenditure of time and labor, and it affords a stable support whereby vibration is to all intent entirely eliminated. The tractor engine 13 is laterally braced to the framework 14 by means of closure plates 17 that take the place of the usual rear-axle housings, and said plates have inclined standard-section struts 18 welded thereto and removably connected at their lower ends by means of flanges 18' to the longitudinal frame sections 15 by bolts 19, or any other convenient means. The front suspension 20 is removably attached by means of a bolt 21, to a vertical lug 22 of appropriate dimension to fit snugly therein, and said lug is spot welded on to the upper flange of the forward transverse section 16 aforesaid, or said suspension may be clamped to the transverse beam web with interposition of appropriate filler plates. Somewhat simi-

larly the rear end of the engine 13 is rigidly braced against lateral displacement by means of opposingly configured vertical lugs 23 spot welded to the upper flange of the 5 rear transverse section 16, and said lugs are positioned to snugly abut the main drive journal housing 24 as will be clearly understood on an examination of Figures 1-3. In like manner, though not essentially so, 10 the engine may be further braced by a transverse saddle plate welded intermediate the sections 16 and adapted for bolting attachment to the body flanges 25.

Referring now to the manner of connecting up my marine unit to the propeller shaft—not shown—it will be firstly observed that I provide the above referred to main drive journal housing 24 with a novel type of thrust bearing closure comprising a main 20 section 26 of rectangular configuration. This main section 26 is clamped to the engine 13 by stud bolts 27, where the previously removed drawbar attachment was formerly located, and said section is formed 25 with an integral box-bearing 28. The bearing 28 serves as a stuffing-box for the connecting shaft 29 splined into the engine transmission and provided at its outer end with a coupling 30 to which the propeller shaft—not shown—is connected in any of 30 the well known ways. In order to prevent seepage of oil and grease beyond the bearing 28, I devised a packing devise—comprehensively designated 31 and best shown in 35 Figures 7 and 8—of removable character and adapted for easy connection and disconnection without displacing the coupling 30 and associated parts. This device 31, it will be seen comprises a gland 32 adjustable by means of stud bolts 33 relative to the thrust bearing 26, and an arcuate removable top 34 for said bearing, the same being attached in place by three stud bolts 35. Thus it will be readily seen that by removing the bolts 35 and loosening the gland 32, the latter can be slid outward on the connecting shaft 29 and the stuffing-box 28 packed—or repacked—as desired, and by a reversal of the operations just set forth the 40 bearing is readily re-adjusted.

Referring again to the framework 14, I desire it to be particularly noted that the longitudinal sections 15 have their webs appropriately apertured to accommodate the transverse sections 16, while said latter sections protrude beyond the outer faces of the longitudinals sufficient to permit electric welding on both sides with a heavy fillet as indicated at 16'. This manner of 55 integrally uniting the longitudinals 16 and horizontals 15 ensures a lock-joint which is at least twice as strong as the ordinary angle-filletted rivet joint.

In order to equip my novel marine unit 60 with an efficient circulating system whereby

it may run cool at all times I firstly remove the ordinary radiator and fan customarily associated in tractors of the type before referred to, and in place thereof I install a small rotary pump, comprehensively designated by the numeral 36. To mount and equip this pump 36 to ensure best results, I employ a base support 37—Figures 9 and 10—having holes 38 therein adapted to register with the customary holes in the front motor support 39,—and to which it is rigidly clamped by bolts 40—at water inlet 41 to the cylinder casting. This base support 37, as best shown in Figure 4 serves as a mounting for the rotary pump 36 which is driven by a reduction gearing 42 direct from the engine shaft 43, as will be readily understood by anyone conversant with the art. It will also be observed that the base support 37 is formed with an embossment 44 to which a bilge or suction connection—not shown—is attached, as well as a pipe nipple 45, for one end of an elbowed pipe 46—having an interposed adjusting union 47—in communication with the inlet side of the pump 36. To afford an outflow or exhaust for the waters of circulation I make use of a plate 48—Figures 5 and 6—secured to the ordinary water outlet 49 in the cylinder head 50 by means of studs or bolts 51 passed through holes 52 in said plate. This plate 48 is also provided with a nipple 52 for an outboard pipe connection 53 to the boat's hull in any convenient location. Thus it will be readily understood that water is 55 constantly circulated through the pump 36 into the engine cylinder jackets, and exhausted out through the pipe 53, whereby I am enabled to keep the engine 13 and immediately associated parts much cooler than has been possible heretofore with a combined radiator and fan.

Referring now to the mechanism operative to control and shift the gears where speed change and reverse, or astern, propulsion obtains, I attach a lever 54 to the customary steering wheel rod 55—said wheel having been previously removed—that is provided at its lower end with a miter couple 56 (Figure 2) effective to turn an elbowed shaft 57 at the left-hand side of the engine. This shaft 57 ordinarily connects with the steering mechanism for the front wheels of the tractor engine, but I pivotally couple said shaft by means of a link 58 to the gear shifter 59. Secured transversely of the engine 13, and conveniently attached to the top of the transmission casing by means of one or more stud bolts 60 is a plate bar 61 having an enlargement 62 apertured at 63 for passage therethrough of the upper end of the gear shifter 59; and said aperture 62 is formed with an inwardly directed undulation 64 for a purpose hereafter fully explained. The plate bar 61 is provided at 68

that side of the engine 13 on which the gear shifter 59 is located with an upwardly directed integral arm 65 to the free end whereof is connected a retractile spring 66, in 5 turn connecting with the link 58 aforesaid. On the right hand side of the tractor engine 13 where the clutch lever 67 extends rearwards I cut off the customary pedal and bend said lever slightly upwards for pivotal connection at 68 of a link 69 in turn 10 pivotally connected to the operating lever 70, fulcrumed at 71 to the side of the tank and steering column support 72, as will be readily seen from an examination of the 15 drawings. Laterally directed from and adjustably connected by locknuts 73 to the aforesaid link 58 is one end of a rod 74, in turn pivoted at 75 to a cam lever 76, fulcrumed to the end of the plate bar 61 at 76' 20 and the lower end whereof is outwardly curved at 77 relative to the vertical, for a purpose hereafter explained; and said cam lever 76 is afforded suitable guidance against lateral displacement, in any of the well 25 known ways. Thus it will be readily understood that, assuming the control mechanism just described is designed for normal retention in the "ahead position," the gear shifter 59 will be automatically held in the 30 notch at the left-hand of the undulation 64 in the plate bar 61. Now when it is desired to reverse or travel "astern" all the attendant has to do is to simply throw the clutch lever 67 full-over or downwards by 35 depressing the operating lever 70 to its full extent. This latter movement, it will be seen, causes the clutch lever 67 to cooperate with and ride upon the outwardly curved end 77 of the cam lever 76 thereby exerting 40 a push to the right-hand upon the rod 74, which effects a correlated movement of the link 58 and gear shifter 59, whereupon the latter will be instantly locked in the notch at the right hand of the undulation 64, upon a swing to the left hand of the lever 45 54. Obviously a vice versa sequence of motions will automatically restore the engine 13 to the "ahead" directional drive. Furthermore, it will be readily understood that 50 if found desirable the aperture 63 may be provided with other notches to lock the engine at half-speed ahead and astern, or at any other predetermined rates of speed. Incidentally, and as will be clearly apparent 55 to those acquainted with the art, by providing the lever 54, 70 with appropriate flexible and universal connections to the wheel house the pilot or captain may control and manoeuvre his boat equipped with 60 my novel marine unit, without an attendant below deck with elimination of the customary signalling device or speaking tube, whereby a boat fitted with said unit is rendered absolutely fool-proof and made one- 65 man navigable.

From the foregoing description it is thought that the numerous advantages and obvious utility of my novel marine unit will be fully appreciated without further explanatory matter, but it is desired briefly 70 to mention some of the more important ones. For example, greater power due to the gear reduction; a simplified control that is fool-proof; economy in use due to the readiness with which worn or damaged parts can be 75 readily replaced anywhere; and the elimination of vibration due to the lock welded frame and quiet mechanical operation.

While I have shown and described an actual embodiment of this invention which 80 has withstood severe tests, it will be obvious the same is susceptible of detail changes, and varied aggroupment of the correlated mechanisms without departing from the true spirit of said invention. Accordingly, the 85 right is hereby reserved to make all such changes and modifications as fairly fall within the scope of the subjoined claims.

Having described my invention, what I 90 claim is:—

1. In a marine unit the combination of a basal framework of lock-welded standard sections, a tractor engine removably supported thereon, means for laterally bracing said engine to the framework, means driven direct from the engine shaft to maintain a continuous cooling circulation thereabout, control mechanism operative by a single manipulating element effective to lock the engine 95 at any desired directional speed, and means whereby the propeller shaft may be repacked without dismantling the coupling connection.

2. In a marine unit the combination of a basal framework of lock welded I-beam sections, a tractor engine removably supported thereon, means for laterally bracing said engine to the framework, means driven direct from the engine shaft to maintain a continuous cooling circulation thereabout, control mechanism operative by a single manipulating element effective to lock the engine 105 at any desired directional speed, and means whereby the propeller shaft may be repacked without dismantling the coupling connection.

3. In a marine unit the combination of a basal framework of lock-welded I-beam longitudinals and horizontals, a tractor engine removably supported thereon, means for laterally bracing said engine to the framework, means driven direct from the engine shaft to maintain a continuous cooling circulation thereabout, control mechanism operative by a single manipulating element effective to lock the engine 120 at any desired directional speed, and means whereby the propeller shaft may be repacked without dismantling the coupling connection.

4. In a marine unit the combination of a 125

basal framework of lock welded I-beam sections, a tractor removably supported thereon, means for laterally bracing said engine and rigidly securing the same on the framework, means driven direct from the engine shaft to maintain a continuous cooling circulation thereabout, control mechanism operative by a single manipulating element effective to automatically lock the engine at any desired directional speed, and means whereby the propeller shaft may be repacked without dismantling the coupling connection.

5. In a marine unit the combination of a basal framework of lock welded I-beam sections, a tractor removably supported thereon, means for laterally bracing said engine and rigidly securing the same on the framework, a reduction drive direct from the engine shaft to a rotary pump for circulating fresh cooling medium continuously thereabout, control mechanism operative by a single manipulating element effective to automatically lock the engine at any desired directional speed, and means whereby the propeller shaft may be repacked without dismantling the coupling connection.

6. In a marine unit the combination of a basal framework of lock welded I-beam sections, a tractor removably supported thereon, means for laterally bracing said engine and rigidly securing the same on the framework, a reduction drive direct from the engine shaft to a rotary pump mounted on the radiator support with supply and exhaust connections whereby fresh water is continuously circulated through the cooling system, control mechanism operative by a single manipulating element effective to automatically lock the engine at any desired directional speed, and means whereby the propeller shaft may be repacked without dismantling the coupling connection.

7. In a marine unit the combination of a basal framework of lock welded I-beam sections, a tractor removably supported thereon, means for laterally bracing said engine and rigidly securing the same on the framework, a reduction gear direct from the engine shaft to a rotary pump mounted on the radiator support, a supply connection through said pump to the engine water inlet and an exhaust connection from the cylinder outlet whereby fresh water is continuously circulated through the cooling system, control mechanism operative by a single manipulating element effective to automatically lock the engine at any desired directional speed, and means whereby the propeller shaft may be repacked without dismantling the coupling connection.

8. In a marine unit the combination of a basal framework of lock welded I-beam sections, a tractor engine removably supported thereon, means for laterally bracing said en-

gine and rigidly securing the same on the framework, means driven direct from the engine shaft to maintain a continuously fresh cooling circulation thereabout, control mechanism operative by a single manipulating element effective to automatically lock the engine in ahead or astern directional speeds, and means whereby the propeller shaft may be repacked without dismantling the coupling connection.

9. In a marine unit the combination of a basal framework of lock welded I-beam sections, a tractor engine removably supported thereon, means for laterally bracing said engine and rigidly securing the same on the framework, means driven direct from the engine shaft to maintain a continuously fresh cooling circulation thereabout, unitary control mechanism operable at a distance for automatically locking the engine at full speed ahead or astern directional drive, and means whereby the propeller shaft may be repacked without dismantling the coupling connection.

10. In a marine unit the combination of a basal framework of lock welded I-beam sections, a tractor engine removably supported thereon, means for laterally bracing said engine and rigidly securing the same on the framework, means driven direct from the engine shaft to maintain a continuously fresh cooling circulation thereabout, means operative from the engine steering wheel shaft to move the engine gear shifter, means coordinated with the clutch actuator, manually operable means effective to throw the clutch simultaneously with a change in the gear drive, and means to automatically lock the gear shifter in any desired directional drive.

11. In a marine unit the combination of a basal framework of lock welded I-beam sections, a tractor engine removably supported thereon, means for laterally bracing said engine and rigidly securing the same on the framework, means driven direct from the engine shaft to maintain a continuously fresh cooling circulation thereabout, a miter couple operable by the engine steering-wheel shaft coordinated with the gear shifter, a connection from the gear shifter means to an oscillatable cam lever, manually operable means coordinated with the clutch actuator adapted to rock the cam lever and effect simultaneous movement of the gear shifter, and means to automatically lock the gear shifter in any desired directional drive.

12. In a marine unit the combination of a basal framework of lock welded I-beam sections, a tractor engine removably supported thereon, means for laterally bracing said engine and rigidly securing the same on the framework, means driven direct from the engine shaft to maintain a continuously fresh cooling circulation thereabout, a miter

couple operable by the engine steering-wheel shaft coordinated with the gear shifter, a spring influenced connection from the gear shifter means to an oscillatable cam lever, 5 manually operable means coordinated with the clutch actuator adapted to rock the cam lever and effect simultaneous movement of the gear shifter, and means to automatically lock the gear shifter in any desired 10 directional drive.

13. In a marine unit the combination of a basal framework of lock welded I-beam sections, a tractor engine removably supported thereon, means for laterally bracing said engine and rigidly securing the same on the framework, means driven direct from the engine shaft to maintain a continuously fresh cooling circulation thereabout, a miter couple from the engine steering wheel shaft 20 to an elbowed member connected by a link to the gear shifter, a spring influenced connection from said link to an oscillatable cam lever, an elbowed extension from the clutch actuator cooperative with the cam lever and 25 adapted to rock the same, and a manually operable linkage arranged to move the clutch actuator whereby the gear shifter is simultaneously operated, and means to automatically lock said shifter for any desired 30 directional drive.

14. In a marine unit the combination of a basal framework of lock welded I-beam sections, a tractor engine removably supported thereon, means for laterally bracing said engine and rigidly securing the same on the framework, means driven direct from the engine shaft to maintain a continuously fresh cooling circulation thereabout, a miter couple from the engine steering wheel shaft 40 to an elbowed member connected by a link to the gear shifter, a spring influenced connection from said link to an oscillatable cam lever, an elbowed extension from the clutch actuator cooperative with the cam lever and 45 adapted to rock the same, and a manually operable linkage arranged to move the clutch actuator whereby the gear shifter is simultaneously operated, and a slotted plate-bar having undulations to automatically 50 lock the gear shifter for any desired directional drive.

15. In a marine unit the combination of a basal framework of lock welded I-beam sections, a tractor engine removably supported 55 thereon, means for laterally bracing said engine and rigidly securing the same on the framework, means driven direct from the engine shaft to maintain a continuously fresh cooling circulation thereabout, a miter 60 couple from the engine steering wheel shaft to an elbowed member connected by a link to the gear shifter, a spring influenced connection from said link to an oscillatable cam lever, an elbowed extension from the clutch 65 actuator cooperative with the cam lever and

adapted to rock the same, and a manually operable linkage arranged to move the clutch actuator whereby the gear shifter is simultaneously operated, and an apertured plate bar having an undulation adapted to 70 automatically lock the gear shifter in high speed for ahead propulsion and in reverse for astern movement.

16. In a marine unit the combination of a basal framework of lock welded I-beam sections, a tractor engine removably supported thereon, means for laterally bracing said engine and rigidly securing the same on the framework, means directly actuated by the engine shaft for continuously circulating fresh cooling water about the engine, a propeller shaft take-off splined into the engine transmission, and a bearing therefor capable of repacking without dismantling 80 the shaft coupling. 85

17. In a marine unit the combination of a basal framework of lock welded I-beam sections, a tractor engine removably supported thereon, means for laterally bracing said engine and rigidly securing the same on the framework, means directly actuated by the engine shaft for continuously circulating fresh cooling water about the engine, a propeller shaft take-off splined into the engine transmission, and a bearing therefor 90 having a removable arcuated top whereby said bearing may be repacked without dismantling the shaft coupling. 95

18. In a marine unit of the type described, the combination of one-man control mechanism effective to automatically lock said unit with any desired directional drive, said mechanism comprising means operative from the engine steering wheel shaft to move the engine gear shifter, means coordinated 100 with the clutch actuator, manually operable means effective to throw the clutch simultaneously with a change in the gear drive. 105

19. In a marine unit of the type described, the combination of one-man control mechanism effective to automatically lock said unit with any desired directional drive, said mechanism comprising a miter couple operable by the engine steering wheel shaft coordinated 110 with the gear shifter, a connection from the gear shifter means to an oscillatable cam lever, manually operable means coordinated with the clutch actuator adapted to rock the cam lever and effect simultaneous movement of the gear shifter. 115 120

20. In a marine unit of the type described, the combination of one-man control mechanism effective to automatically lock said unit with any desired directional drive, said mechanism comprising a miter couple from the engine steering wheel shaft to an elbowed member connected by a link to the gear shifter, a spring influenced connection from said link to an oscillatable cam lever, an elbowed extension from the clutch actuator 125 130

ator cooperative with the cam lever and adapted to rock the same, and a manually operable linkage arranged to move the clutch actuator whereby the gear shifter is 5 simultaneously operated.

21. In a marine unit of the type described, the combination of one-man control mechanism effective to automatically lock said unit with any desired directional drive, said 10 mechanism comprising a miter couple from the engine steering wheel shaft to an elbowed member connected by a link to the gear shifter, a spring influenced connection from said link to an oscillatable cam lever,

an elbowed extension from the clutch actuator cooperative with the cam lever and adapted to rock the same, and a manually operable linkage arranged to move the clutch actuator whereby the gear shifter is simultaneously operated, and an apertured plate 20 bar having an undulation adapted to automatically lock the gear shifter in high or reverse drive for the purpose specified.

In testimony whereof I affix my signature the 31st day of July, 1924, at Philadelphia, 25 Pennsylvania.

JOSEPH S. OECHSLE.
